US00D537201S

(12) **United States Design Patent** (10) **Patent No.:** **US D537,201 S**
(45) **Date of Patent:** **** Feb. 20, 2007**

(54) **CAPSULE**

(75) Inventors: **Andrew Robert McLeish**, deceased, late of South Yorkshire (GB); by **Natalie McLeish**, legal representative, South Yorkshire (GB)

(73) Assignee: **Reckitt Benckiser N.V.**, Hoofddorp (NL)

(**) Term: **14 Years**

(21) Appl. No.: **29/221,854**

(22) Filed: **Jan. 21, 2005**
(Under 37 CFR 1.47)

Related U.S. Application Data

(63) Continuation-in-part of application No. 29/188,151, filed on Aug. 13, 2003, now Pat. No. Des. 505,516, which is a continuation-in-part of application No. 29/152,745, filed on Dec. 27, 2001, now abandoned.

(57) **CLAIM**

The ornamental design for a capsule, as shown and described.

DESCRIPTION

The file of this patent or application contains at least one drawing or photograph executed in color. Copies of this patent or patent application publication with color drawings will be provided by the Patent and Trademark Office upon request and payment of the necessary fee.

FIG. 1 is a top perspective view of a capsule showing a first embodiment of my new design;

FIG. 2 is a top plan view thereof;

FIG. 3 is a front elevational view thereof, a rear elevational view thereof being the same;

FIG. 4 is a right-side elevational view thereof, a left-side elevational view thereof being the same;

FIG. 5 is a bottom plan view thereof;

FIG. 6 is a top perspective view of a capsule showing a second embodiment of my new design;

FIG. 7 is a top plan view thereof;

FIG. 8 is a front elevational view thereof, a rear elevational view thereof being the same;

FIG. 9 is a right-side elevational view thereof, a left-side elevational view thereof being the same;

FIG. 10 is a bottom plan view thereof;

FIG. 11 is a top perspective view of a capsule showing a third embodiment of my new design;

FIG. 12 is a top plan view thereof;

FIG. 13 is a front elevational view thereof, a rear elevational view thereof being the same;

FIG. 14 is a right-side elevational view thereof, a left-side elevational view thereof being the same;

FIG. 15 is a bottom plan view thereof;

FIG. 16 is a top perspective view of a capsule showing a fourth embodiment of my new design;

FIG. 17 is a top plan view thereof;

FIG. 18 is a front elevational view thereof, a rear elevational view thereof being the same;

FIG. 19 is a right-side elevational view thereof, a left-side elevational view thereof being the same; and,

FIG. 20 is a bottom plan view thereof.
